UNITED STATES PATENT OFFICE.

AXEL G. GULBRANSEN, OF CHICAGO, ILLINOIS, ASSIGNOR TO GULBRANSEN, DICKINSON COMPANY, OF CHICAGO, ILLINOIS, A CORPORATION OF ILLINOIS.

PNEUMATIC FOR MECHANICAL MUSICAL INSTRUMENTS.

No. 891,930.

Specification of Letters Patent.

Patented June 30, 1908.

Application filed September 12, 1906. Serial No. 334,241.

To all whom it may concern:

Be it known that I, AXEL G. GULBRANSEN, citizen of the United States, residing at Chicago, in the county of Cook and State of Illinois, have invented a certain new and useful Improvement in Pneumatics for Mechanical Musical Instruments, of which the following is a full, clear, concise, and exact description, reference being had to the accompanying drawings, forming a part of this specification.

My invention relates to primary pneumatic mechanisms, particularly to such mechanisms adapted to be used in mechanical musical instruments, such as pianos, and the object of my invention is to provide more simple, more compact and more efficient construction and arrangement of such mechanisms.

The various features of my invention will be best understood and described by reference to the accompanying drawing, in which

Figure 1 is a side view of a pneumatic mechanism; Fig. 2 is a top view thereof; Fig. 3 is a sectional view taken on plane 3—3 of Fig. 1; Fig. 4 is a top view, the part above plane 4—4 of Fig. 1 being removed; and Fig. 5 is a vertical sectional view taken on plane 5—5 of Fig. 2.

The primary pneumatic mechanism here shown is adapted for association with the abstract rods of a piano, and the bellows and valve mechanisms are all comprised in a small and compact unitary structure, these various structures, as described in my co-pending application, Serial No. 331,230, filed August 20, 1906, being arranged in staggered rows, and connected at their front ends with the rear wall of the low pressure chamber running along the lower part of the piano casing to the rear of the drop board. This low pressure chamber is represented in the drawing by 1, the primary pneumatic mechanisms being screwed to its rear wall 2 by means of screws 3. Each primary mechanism has a main mounting block 4 from the lower side of which are suspended any number of bellows 5, 6, and so on, arranged in a vertical tier, the swinging members 7 of the bellows being all connected together through links 8, and one of the swinging members having a cushioned abutment or extension 9 for engagement with some member connecting with the hammer-actuating mechanism of the instrument. In the front end of the mounting block are the upper and lower dia-

phragm chambers 10 and 11 separated by the diaphragm 12 whose edges are glued to the annular ledge 13 between the chambers. In the rear of the mounting block are the upper and lower auxiliary diaphragm chambers 14 and 15 separated by the auxiliary diaphragm 16 secured at its edges to the annular ledge 17 between the chambers. Secured over the mounting block is the valve block 18 which forms the roof of the upper diaphragm chambers 10 and 14. Concentric with the main diaphragm chambers is the valve chamber 19 in the valve block in which is the ball valve 20 which may be of any material but is preferably in the form of a hollow aluminum ball. Secured to the valve block below the valve chamber is the washer 21 which forms a seat for the valve, and over the valve chamber is secured the washer 22 which forms a seat for the valve when the valve is raised. Concentric with the auxiliary diaphragm chambers is the opening 23 through which extends a valve stem 24 having the upper and lower valve heads 25 and 26, the lower valve head being in position to be engaged by the auxiliary diaphragm when said diaphragm is raised. In the center of the main diaphragm is a block 27 for engaging with the valve when the main diaphragm is raised.

A channel or passageway 28 leads from the rear end of the valve block and passes through the valve block to a vertical passageway 29 which connects with the passageway 30 leading through the main mounting block to the lower auxiliary diaphragm chamber 15. The chamber or opening 23 is connected with the lower main diaphragm chamber 11 through passageways 31 and 32 through the valve and mounting blocks, respectively. The upper diaphragm chambers connect together through the passageway 33, and the upper main diaphragm chamber connects with the low pressure chamber 1 through passageways 34 and 35 cut respectively in the mounting block and rear wall 2. The passageway 28 communicates with the trackerboard through the passageway 36 and is also in communication with the low pressure chamber through passageway 37 over whose outlet is secured the washer or disk 38 having the pin hole or perforation 39. The valve chamber 19 connects with the lower bellows 6 through channels 40 and 41 and is connected with the

upper bellows through channels 42 and 43, as best shown in Fig. 3.

Normally the ball valve rests on its lower seat 21 and away from its upper seat 22, the valve chamber 19 and the bellows connected therewith being thus in communication with atmosphere and the bellows distended. The auxiliary valve is normally also in its lower position, its upper head 25 closing the chamber 23 to atmosphere and connecting said chamber with the upper auxiliary diaphragm chamber. Normally low pressure air from the low pressure chamber has access to all the diaphragm chambers when the diaphragms are down. This air passes to the upper diaphragm chambers through the passageways 34, 35, and the connecting passageway 33, the lower main diaphragm chamber being normally in communication with the upper auxiliary diaphragm chamber, and the lower auxiliary diaphragm chamber receiving this low pressure air through the perforation 39 and passageway 36. As the music sheet, however, travels over the trackerboard the passageway 36 is opened and atmospheric air immediately rushes down said passageway into the passageway 28 and into the lower auxiliary diaphragm chamber, causing the auxiliary diaphragm to be quickly blown upwardly, the lower valve head being raised to close the lower opening of the chamber 23, and the upper valve head 25 being raised to connect said chamber with atmosphere. Atmospheric air therefore immediately rushes into chamber 23 and through passageways 31 and 32 to the lower main diaphragm chamber, causing the main diaphragm to be blown upwardly, whereupon the block 27 strikes the ball valve and this valve is raised from its lower seat into engagement with its upper seat. The connection to atmosphere from the valve chamber is therefore closed and the valve chamber connected directly with the low pressure chamber 1, and the bellows are therefore then also connected with the low pressure chamber and immediately collapse, these bellows acting all cumulatively, their combined force being transferred to the abutment 9 through the connecting rods and to the part of the piano to be actuated. The pin hole opening 39 being so very small, the entire force of the atmospheric air rushing through and down passageway 36 is utilized in operating the auxiliary valve. The only function of this auxiliary valve is to connect the lower main diaphragm chamber directly with atmosphere through a large passageway. This arrangement eliminates the necessity of having adjusting mechanisms whereby the music sheet may be adjusted with relation to the trackerboard in order to assure that the music sheet openings at all times register exactly with the trackerboard openings. With

this arrangement of primary mechanism the music sheet openings need not be very large but can be very much narrower than the trackerboard openings, as very little atmospheric air is required to operate the auxiliary valve. This auxiliary valve is more in the nature of a relay valve, just sufficient air being necessary to raise the valve so that the lower main diaphragm chamber can be directly connected with atmosphere through a large passageway, and the air coming in through this large passageway operates the main diaphragm and valve instead of the air admitted through the music sheet. Thus the music sheet may be allowed a wide range of displacement or relative movement with respect to the trackerboard without in any way influencing the amount of air admitted to operate the auxiliary valve. When the music sheet again closes the trackerboard opening the valves fall back to their normal position, for the reason that the air below the diaphragms returns to normally low pressure by virtue of the equalizing pin hole opening 39. The bellows become distended immediately after the ball leaves the seat 22 and allows atmospheric air to flow to the bellows. Although auxiliary valving mechanism may have been used in connection with primary valving mechanism, I think I am the first to incorporate such mechanisms together with the bellows in a unitary, small and compact structure as shown. As described in the co-pending application referred to, the paralleling of bellows as I have described is much more efficient in results, as the response of the bellows to opening of the trackerboard passageways is much quicker than any mechanisms where the single, comparatively long bellows are employed. This paralleling of the bellows also assists in producing a compact structure, as there is always more room up and down in an instrument such as a piano, than there is room horizontally.

Having thus described my invention I claim as new and desire to secure by Letters Patent the following claims:

1. In pneumatic mechanism for mechanically operated pianos, the combination of a main supporting block 4, a bellows 5 directly below the mounting block, said mounting block forming the top of said bellows, a second bellows 6 supported from the mounting block and disposed directly below the bellows 5, a rod 8 connecting the movable parts of the bellows, a valve chamber 11, a diaphragm in said chamber, a valve block 13 over the mounting block; a valve opening 19 through said valve block, a ball valve 20 controlling said opening and disposed directly above the diaphragm to be actuated thereby, a secondary valve outlet 23 through the valve block, a spool-shaped secondary valve 24 having an outside head 25 and an inside

head 26, a second diaphragm chamber 15, a diaphragm 16 in said chamber for controlling the movements of the secondary valve, a reservoir, connections between the reservoir and the diaphragm chambers, and a connection between the reservoir and bellows controlled by the valves.

2. In pneumatic mechanism for mechanically operated pianos, the combination of a supporting frame forming a reservoir, a valve block supported and extending from said supporting frame, a bellows below the block, said block forming the stationary upper wall of the bellows, a valve block on the supporting block, an outlet through said valve block to atmosphere, a ball valve controlling said outlet, a diaphragm chamber within the supporting block, a diaphragm within the diaphragm chamber for controlling the operation of the ball valve, a second opening through the valve block, a spool-shaped

secondary valve controlling the flow through said second passageway, a second diaphragm chamber, a diaphragm in said second diaphragm chamber for controlling the operations of the secondary valve, an outlet to atmosphere, connections between the diaphragm chambers and the reservoir, opening of said atmosphere outlet causing actuation of the secondary valve to connect the first 30 diaphragm chamber with atmosphere to cause actuation of the ball valve, and connections between the bellows and reservoir opened upon such actuation of the ball valve.

In witness whereof, I hereunto subscribe 35 my name this 8th day of September A. D., 1906.

AXEL G. GULBRANSEN.
